CONTAINER BAG AND OUTER GARMENT

Marie A. Byrd, Boston, Mass.

Application May 14, 1941, Serial No. 393,360

1 Claim. (Cl. 2—48)

The present invention relates to bags suitable for carrying knitting supplies or for any other of a variety of uses, the bag being designed and constructed for convenient attachment to the body of a person using the same and adapted to serve both as a bag of particularly advantageous construction and as an outer garment for the user.

It is an object of the invention to provide an improved bag of this type. The bag of the present invention has an opening which is adjustable but may be extremely large and, as the bag is attached to the person of the user, it is convenient merely to drop into it articles such as knitting supplies, sewing or the like, when it is necessary for the user to move from one place to another. At the same time, the bag may be neatly closed, at which time it has the appearance of an apron or other garment and may serve either the function of a garment, bag, or both. The bag is of durable construction, easily put on and taken off and adapted to fit nicely to the body of the wearer. Other objects and advantages of the invention will be apparent from the ensuing more particular description and from the accompanying drawing, wherein—

Fig. 1 is a plan view of a bag made according to the invention; and

Fig. 2 is a sectional view on the line 2—2 of Fig. 1.

Referring to the accompanying drawing, the combined bag and apron of the invention has an upper or waist portion 10 formed of suitable durable fabric. To the upper edge of the portion 10 is secured a strap 12 provided at one end with a buckle 14, said end of the strap being adapted to extend around the waist of the wearer and to be attached to the opposite end of the strap by means of the buckle 14 to support the apron. Strap 12 may conveniently be made of one or more plies of the material forming the body portion 10, turned over at the top edge and secured together, and to the body portion 10, by rows of stitching 16 along the bottom edge. The upper part of the upper body portion 10 of the apron may be provided between its side edges with pleats 18 secured by vertical lines of stitching 20. The pleats 18 not only enhance the ornamental appearance of the apron, but also enable this portion to fit neatly about the waist of the wearer.

To the lower edge of the waist portion 10 is secured, by a horizontal row of stitching 22, a pouch or bag 24 forming the lower body portion or skirt of the apron and extending the full width of the portion 10. As shown in Fig. 2, bag 24 is made of a sheet of fabric folded over intermediate its ends at 26 and secured together at its side edges 28, 30 by stitching (not shown)

to form a pocket, of the same width as the lower edge of the portion 10 and, in the form shown, of greater length than said portion, having a front flap 32 and a rear flap 34, the front flap 32 being slightly shorter than the rear flap as shown.

The bag 24 is adapted to be opened and closed by a slide fastener of usual form having complementary rows of teeth 36 and 38 attached to tapes 40 and 42 secured by stitching to the inner surfaces of the upper edges of the front and rear flaps respectively, and a slide 44 adapted to be reciprocated between the rows of teeth to lace and unlace them.

10 Preferably, the tapes 40 and 42 are sewn to the fabric before the latter is folded, the fabric is then folded, and sewn at the edges, with the fabric surfaces carrying the tapes on the outside instead of on the inside as shown, and the pouch 15 is then turned inside out and sewn at the upper edge of rear flap 34 to the portion 10 by the stitching 22 which passes through the tape 42 as well as the fabric of the portion 10 and rear flap 34. The seams at the sides of the pouch are thus 20 on the inside and concealed from view, enhancing 25 the appearance of the bag.

There is thus provided a bag of neat, attractive appearance, well adapted to serve the dual function of providing a conveniently accessible pouch 30 of large capacity in which bulky articles may be readily placed and carried and at the same time to serve as an outer garment. The slide fastener closure for the pouch not only provides an easily operated, efficient seal for the pouch, 35 but also serves to prevent unsightly sagging of the front flap of the pouch under the weight of articles carried therein.

Having described and claimed a preferred embodiment of the invention, what I desire to 40 claim and secure by Letters Patent is:

As an article of manufacture, a combined garment and bag comprising a skirt portion of substantially rectangular formation and formed of a length of fabric turned over intermediate its 45 ends and sewn together at its edges to form a bag having front and rear flaps free of each other between said sewn edges and presenting an access opening at the upper edge of the bag, a waist protector portion formed of a piece of 50 fabric attached to said rear flap and extending a substantial distance above said skirt portion, means on said waist protector portion for securing same about the waist of a wearer, said waist portion and means being insertible in said bag 55 portion, and means for closing said access opening with or without said waist portion and means therein.
